UNITED STATES PATENT OFFICE.

WILLIAM J. KENT, OF BROOKLYN, NEW YORK, ASSIGNOR TO REVERE RUBBER COMPANY, A CORPORATION OF RHODE ISLAND.

DESIGN FOR A HORSESHOE-PAD.

53,635.

Specification for Design.

Patented July 22, 1919.

Application filed September 1, 1915. Serial No. 48,557. Term of patent 14 years.

To all whom it may concern:

Be it known that I, WILLIAM J. KENT, a citizen of the United States, residing at Brooklyn, county of Kings, and State of New York, have invented a new, original, and ornamental Design for Horseshoe-Pads, of which the following is a specification, reference being had to the accompanying drawing, forming part thereof, wherein—

The figure is a perspective view of a horseshoe pad showing my new design.

I claim:

The ornamental design for a horseshoe pad as shown.

Signed at 290 Broadway, New York city, N. Y., this 26th day of August, 1915.

WILLIAM J. KENT.

Witnesses:

MARTIN J. BEVANS,
H. METCALFE.
